2 Sheets-Sheet 2

UNITED STATES PATENT OFFICE.

CURT NEUBAUER, OF MECKLENBURG, GERMANY.

PROCESS OF AND DEVICE FOR DRAWING BELLIED OBJECTS OF SHEET METAL.

Application filed September 17, 1921. Serial No. 501,417.

To all whom it may concern:

Be it known that I, CURT NEUBAUER, mechanical engineer, a citizen of the German Republic, residing at Slüterufer 3, Schwerin

5 i. Mecklenburg, Germany, have invented certain new and useful Improvements in or Relating to a Process of and Device for Drawing Bellied Objects of Sheet Metal, of which the following is a specification.

10 My invention relates to a process of and a device for drawing bellied objects of sheet metal. Bellied objects of sheet metal have heretofore been pressed or drawn in presses by means of positive and negative tools or

15 made by the so-called rolling process. The process mentioned in the first place is admissible for certain dimensions only of the sheet objects. For large parts the pressure increases into such a degree that the process

20 ceases to be economical and the necessary pressing moulds are impossible to make on account of technical reasons. The rolling process which consists in the sheet being pressed into a hollow mould by means of a

25 regularly shaped spherical or rounded pressing roll is applicable only when the transitions in the hollow shape are gradual, while deep excavations require numerous operations so that the process becomes expensive

30 in time and cost.

The present invention avoids the drawbacks of both known processes by the sheet to be worked being drawn between a profiled developing drawing tool and a corresponding counter-mould of the shape intended.

According to this process the counter-mould bears the outer shape of the object to be manufactured, while the developed surface of the drawing tool shows its inner shape. In certain cases the developed surface of the drawing tool or of the counter-mould may be interrupted by gaps or hollows.

45 This process is suitable for unskilled hands and affords the advantage of the pressure required being moderate so that as a rule a single operation will be sufficient; rarely two or even more operations will be required. The new process will allow the moulding of

50 large sheets.

With powerful drawing machines the process is also suitable for thick plates and strips. The tools required are much cheaper than the press moulds because they are of simpler construction and in most cases are sufficiently strong when made of hard wood.

The drawing represents three instances of execution, namely—

Fig. 1 is a section through the tools required for making the shell of a boat according to the present invention,

Fig. 2 is a cross section through Fig. 1 and shows the cross section of the boat in dotted lines.

Fig. 3 is a side view of a device for making the rear wall of a motorcar body.

Fig. 4 is a cross section through Fig. 3 and

Fig. 5 is the counter-mould for making an object of sheet metal with double curvature.

A slightly modified form of construction is illustrated in Figs. 6 and 7 in which a rotary counter-mould instead of a reciprocating one is provided, Fig. 6 being a transverse section and Fig. 7 a longitudinal section.

In the arrangement according to Figs. 1 and 2 the sheet is drawn between a developing tool and a flat counter-mould, the latter making a progressive forward movement relatively to the axis of the drawing tool or vice versa. The circumference of the drawing tool is an exact evolution of the inner shape of the object to be formed. The evolution may be completed either with a

full or a partial revolution of the tool. The length of the counter-mould into which the sheet is pressed while the tool is operated and the surface of which exactly corresponds to the outer shape of the object to be manufactured must therefore equal the length of

90 the evolution of the tool. In most cases the sheet worked need not necessarily contact both tools; only the convex surface must be in full contact with the sheet while the concave surface may be provided with hollows into which the convex part presses the sheet, so that the concave surface may differ from the exact shape of the object to be made. The edges of the sheet are secured

95 either in full length or partially by means of corresponding fixing devices.

In the arrangement according to Figs. 1 and 2 showing the manufacture of one half of a boat shell *a* is the drawing tool. The surface *b*—*c* exactly corresponds with the evolution of the inner surface of the boat's

100 half. The drawing tool *a* revolves around the axle *d* mounted in two bearings (not shown in the drawing), which when the counter-mould performs a forward movement, are fixed to the machine frame. The

105 counter-mould *e* may have a surface exactly

110

corresponding to the outer shape of the object to be manufactured or, as the figure shows, may consist of a body provided with a hollow space *f* between the surfaces whereupon the sheet is fixed so that the convex part of the drawing tool may freely enter. The frame *g* serves to keep down the sheet *h* upon the fixing surfaces of the counter-mould.

- 10 Before the drawing operation the sheet *h* assumes the straight position marked in Fig. 2 by dotted lines. The frame *g* presses the sheet upon the fixing surfaces of the mould *e* the pressure being limited to an amount 15 which enables the sheet to be gradually pulled out under the fixing frame *g* while being worked without being bulged or plaited. As soon as the counter-mould *e* with the sheet *h* fixed to it is moved forward 20 under the drawing tool *a* mounted in fixed bearings the tool turns around its axle *d*. The tool surface *b*—*c* then acts on the sheet *h* and presses the same into the counter-mould *e*, the sheet being at the same time 25 pulled out to a certain extent under the frame *g*. The borders which are left outside of the shaped portion are trimmed off after the sheet has been taken out of the counter-mould.
- 30 For very deep forms the height of the drawing tool *a* can be adjustable in order to perform the process in several consecutive operations. In Fig. 2 the other half completing the shell of the boat is likewise 35 shown in dotted lines.

It results from the description of the new process that the work need not necessarily be symmetrical in shape. It may be deeper in one place than in another. Its width may 40 vary and terminate in a point. The sheet to be worked may also be fixed in an inclined position under the frame before being drawn, and the horizontal and straight position can be done away with; the sheet may 45 also be bent before the drawing operation as e. g. for the rear wall of a motorcar body, the manufacture of which is represented in Figs. 3 and 4. Fig. 3 shows the bent sheet in dotted lines. In this case the counter-mould *i* is convex and the drawing tool concave, the counter-mould therefore representing the shape of the work in an uninterrupted 50 surface, while the drawing tool consists of two parts *l* and *m* with the developing surfaces *n*—*o* and *p*—*q* respectively. The sheet *j* is to be inserted in a shape perpendicularly bent with respect to the axis of the drawing tool (Fig. 3) and in a position shown by dotted lines in Fig. 4. The reference letter *k* indicates the fixing beams or fixing frame intended to hold down the sheet at both edges in analogy with the fixing frame *g* in Figs. 1 and 2, yiz. in order to 55 avoid bulging and plaiting of the sheet.

60 As soon as the counter-mould is moved in

a lengthwise direction, both tools *l* and *m* are operated, thus partly extracting the sheet from under the fixing beams and pressing it into the sharp edges at both sides. In this way the sheet is also drawn over the 70 convex part in the middle of the section and fitted to its shape even if the space between both parts *l* and *m* remains hollow.

The manufacture of an object the concavity of which is interrupted by a ridge (as per Fig. 5) is enabled by a counter support *r* in the corresponding place of the mould. The evolution of shapes of this class is to be confined to the drawing tool as in the other cases referred to.

The relative movement between drawing tool and counter-mould can be determined at will, e. g. the latter may be fixed and the first may travel inasmuch as the axle is moved in a horizontal direction.

The dependence of the rotation of the drawing tool upon the travel of the counter-mould or vice versa to the end of producing a correct evolution of the parts upon each other may be secured either by friction or by means of suitable gearing such as cog-wheels and racks, worm-wheels, screw spindles etc., which prevent a displacement not intended while the evolution is being performed.

Concerning now the form of construction illustrated in Figs. 6 and 7, this is distinguished from that shown in Figs. 1-5 by the feature that instead of the reciprocating counter-mould a rotary one is employed. In all other respects, the combination and arrangement of the parts may be the same as already described. The upper tool *a'* is attached to the rotatable shaft *d'*, and the counter-mould *s* is secured to a shaft *t* which is rotated with the same speed and in the same manner as the shaft *d'*. The stationary bed 17 of the machine supports then solely the reciprocating clamping device 34 into which the piece of sheet-metal 35 to be worked is placed. The clamping-device 34 may be driven in any desired manner, for instance by a cog-wheel 36 which meshes with a laterally arranged rack 37.

For the tools as well as for the counter-moulds any suitable material may be used. In certain cases hard wood is sufficient, but steel, cast iron, etc., may also be applied.

What I claim is:

1. A process for drawing bellied sheet metal articles, consecutive sections of which, in the drawing direction, differ in shape from one another, comprising the steps of drawing a metal sheet between a rotary drawing tool and a synchronously-moved coacting counter-mould, while imparting to the sheet a progressive forward bodily movement in the direction of its length and relative to the axis of the drawing tool, so as to cause said tool to act progressively upon

the sheet from end to end thereof, and maintaining the distance between the tool axis and the plane of the mould constant during the entire movement of the sheet; substantially as described.

2. A process for drawing bellied sheet metal articles, consecutive sections of which, in the drawing direction, differ in shape from one another, comprising the steps of 10 positioning a metal sheet upon a counter-mould, drawing the sheet between the tool and mould while imparting to the mould a progressive forward bodily movement in the direction of its length and relative to the 15 tool axis so as to cause the tool to act progressively upon the sheet from end to end thereof, and maintaining the distance between the tool axis and the plane of the mould constant during the entire movement 20 of the mould; substantially as described.

3. Apparatus for drawing bellied sheet metal articles, consecutive sections of which, in the drawing direction, differ in shape from one another, comprising a rotary drawing tool, a counter-mould coacting with the drawing tool and movable synchronously therewith, and means for moving the metal sheet to be drawn between and synchronously with the said coacting elements and progressively forward bodily in the direction of its length without varying the distance between the tool axis and the plane of the mould, so as to cause the drawing tool to act 25 progressively upon the sheet from end to end thereof; substantially as described.

4. Apparatus for drawing bellied sheet metal articles, consecutive sections of which, in the drawing direction, differ in shape from one another, comprising a rotary drawing tool having a circumferential working surface which is a progressive evolution of the successive portions of the inner surface of the article to be drawn, a counter-mould coacting with the drawing tool and movable 40 synchronously therewith and having a working surface which corresponds in shape to the outer surface of said article and in length to the length of said tool surface, and means

for moving the metal sheet to be drawn between and synchronously with the said coacting elements and progressively forward bodily in the direction of its length without varying the distance between the tool axis and the plane of the mould, so as to cause the drawing tool to act progressively upon 50 the sheet from end to end thereof; substantially as described.

5. Apparatus for drawing bellied sheet metal articles, consecutive sections of which, in the drawing direction, differ in shape 55 from one another, comprising a rotary drawing tool, a counter-mould on which the metal sheet to be worked is adapted to be positioned coacting with the drawing tool, and means for imparting to the mould and 60 the sheet thereon synchronously with the rotation of the tool a progressive forward bodily movement in the direction of its length and relatively to the tool axis without 65 varying the distance between the tool axis and the plane of the mould, so as to cause the drawing tool to act progressively upon 70 the sheet from end to end thereof; substantially as described.

6. Apparatus for drawing bellied sheet metal articles, consecutive sections of which, in the drawing direction, differ in shape 75 from one another, comprising a rotary drawing tool, a counter-mould on which the metal sheet to be worked is adapted to be positioned coacting with the drawing tool, means 80 for clamping the sheet in place on the mould, and means for imparting to the mould and the sheet thereon synchronously with the rotation of the tool a progressive forward bodily movement in the direction of its length and relatively to the tool axis without varying 85 the distance between the tool axis and the plane of the mould, so as to cause the drawing tool to act progressively upon the sheet from end to end thereof; substantially as described.

In testimony whereof I have affixed my signature.

CURT NEUBAUER.
